UNITED STATES PATENT OFFICE.

GEORGE ROWBOTTOM, OF WATERBURY, CONNECTICUT, ASSIGNOR TO AMERICAN PIN COMPANY, OF WATERBURY, CONNECTICUT, A CORPORATION OF CONNECTICUT.

MACHINE FOR SEWING HOOKS AND EYES ON CARDS.

SPECIFICATION forming part of Letters Patent No. 710,519, dated October 7, 1902.

Original application filed May 1, 1901, Serial No. 58,289. Divided and this application filed October 10, 1901. Serial No. 78,162. (No model.)

To all whom it may concern:

Be it known that I, GEORGE ROWBOTTOM, a citizen of the United States, residing at Waterbury, in the county of New Haven and 5 State of Connecticut, have invented certain new and useful Improvements in Machines for Fastening Hooks and Eyes on Cards, of which the following is a specification.

This invention relates to improvements in 10 card-feeding mechanism for hook-and-eye-fastening machines, the present invention being a division of my application, Serial No. 58,289, filed May 1, 1901. In that application is disclosed a machine for fastening hooks 15 and eyes on cards and comprising means for feeding the hooks and eyes to the card, means for intermittently feeding the cards in proper position to receive the hooks and eyes, and means for sewing the hooks and eyes on the 20 cards. The present application relates only to the card-feeding means, and only so much of the other mechanism is herein included as is necessary to an understanding of this invention.

25 The object of the present invention is to provide for an extra feed of the cards when the operation is passing from one card to the next, this extra feed being necessary on account of the spaces at the ends of the cards 30 and between the cards.

In the accompanying drawings, Figure 1 is 35 a horizontal section on the line *a a* in Fig. 2 of a machine embodying my invention. Fig. 2 is a vertical section on the line *b b* in Fig. 1. Figs. 3 and 4 are partial elevations of the feed-operating mechanism in two different positions.

The hook-and-eye feeding and gripper mechanisms have been omitted from the drawings, as they do not relate to the present invention, and only so much of the other mechanism of the machine is shown as co-operates directly with the card-feeding mechanism and is necessary to an understanding thereof.

45 The machine is made to work in duplicate—that is, to simultaneously attach the pairs of hooks and eyes in two rows on the cards—and the machine itself is therefore also duplicate, each operative part being, in general, dupli-

cated on the two sides of the machine. All ,o the parts are supported on a suitable bed, table, or frame 1, which is provided with a central bracket 2 for the needle-bar mechanism on a standard 3. In the center of the bed 1 is arranged a table 9, on which the 55 cards are fed as the sewing is effected. The main driving-shaft 5, carrying the driving-pulley 6, with clutch 7, is journaled in suitable bearings in the machine-frame.

The card-feeding mechanism comprises a 60 track or way for receiving the cards, defined by guides 67 on the table 9, and feed-rolls 70 71, arranged in two series, respectively, below and above said track and engaging frictionally with the cards. The upper feed-rolls are 65 provided with adjustable spring-tension devices 68. The lower rolls 70 are connected by gears 75 with a shaft 76, carrying a ratchet-wheel 77, which is engaged by a pawl 78 on an arm or lever 79, to which is pivoted one 70 end of a bar 80, whose other end is forked and slides over a hub 81 on the shaft 5. A cam 85 on this shaft 5 engages a roll 82 on the bar 80, and a spring 86 is arranged to press this roll toward the cam, said spring being 75 connected at one end to the standard 3 and at the other end to a link 83, pivoted to a bell-crank 66, which is also pivoted on standard 3 and engages a pin 84 on the bar 80. Cam 85 has two projecting portions, which 80 cause the bar 80 to reciprocate twice in each rotation of shaft 5, and there are consequently two feeding movements of the feed-rolls for each such rotation, for each such rotation results in the delivery of a single pair of hooks 85 and eyes on each side of the card, and as each eye and hook has two sewing-eyes there must be twice as many stitches and twice as many feeding movements as there are pairs of hooks and eyes in each row. The article-fastening 90 means therefore acts to fasten the articles (pairs of hooks and eyes) on the cards between actions of the card-feeding means. At intervals, owing to the filling of one card and the passage to the next, it is desirable to make 95 an extra feed without stitching, and to this end I provide a stop-disk 88 on a stud-shaft 215, fixed on a frame-block 216 and carrying

also a ratchet-wheel 218, engaged by a pawl 219 on the reciprocating feed-bar 80, so that said stop-disk is turned in accordance with the feed of the cards. This stop-disk is provided with notches 89 therein, adapted to receive a lug 90 on the bar 80. Said lug normally rests against the periphery of said stop-disk, and thereby limits the back stroke of the bar 80, so that only a limited feed is effected, sufficient to carry the card the distance from one sewing-eye to the next; but in each semirevolution of disk 88, corresponding to the length of a card, a notch 89 permits a greater back movement of the feed-bar 80, and the next action of the cam 85 will cause a correspondingly greater forward stroke and give an extra feed.

Having thus described my invention, the following is what I claim as new therein and desire to secure by Letters Patent:

1. In a machine for fastening articles on cards, a card-feeding means comprising feed-rolls, ratchet mechanism operating same, a reciprocating bar operating said ratchet mechanism, a stop device controlling the movement of said bar, and provided with a

notch permitting at intervals a longer feed operation of said bar, ratchet-wheel and rolls.

2. In a machine for fastening articles on cards, the combination of the feed-rolls, ratchet-wheel connected thereto, bar carrying a pawl engaging said wheel, a cam operating said bar, a spring for moving said bar toward the cam, and a stop-disk engaging with said bar to limit its movement toward the cam and connected to be rotated by the reciprocation of said bar by a pawl-and-ratchet connection and provided with a notch permitting at intervals a longer operation of said bar to give an extra feed.

3. In a machine for fastening hooks and eyes on cards, an intermittently-acting card-feeding means provided with controlling devices whereby an extra feeding motion is given at the end of every card, in combination with fastening means for fastening articles on the card between feeding actions of the card-feeding means.

GEORGE ROWBOTTOM.
